SCAVENGE SYSTEM FOR ENGINES

Andrew Kalitinsky, Eagleville, Conn., assignor to
 United Aircraft Corporation, East Hartford,
 Conn., a corporation of Delaware

Application May 11, 1943, Serial No. 486,611

16 Claims. (Cl. 123—51)

1
 The present invention relates to an air scavenging system for an opposed piston engine and is especially adapted for a free-piston engine-and-compressor unit.

In conventional opposed piston engines the scavenging ports are at one end of the engine cylinder and the exhaust ports at the opposite end. When the ports are uncovered by the pistons, the cool scavenging air enters one end of the cylinder and pushes the burned gases out of the exhaust ports at the other end. The cool air passes over, and cools, the head of the piston adjacent the scavenging ports, but the other piston is continuously subjected only to the high temperatures of the burned gases. An object of this invention is to provide for directing cool scavenging air onto the heads of both pistons.

This object is accomplished by providing scavenging ports at both ends of the engine cylinder so that the scavenging air enters the cylinder over the heads of both pistons. For efficient removal of the burned gases, however, the general flow of the gases should be in one direction from one end to the other of the engine cylinder. One feature of the invention provides for maintaining a general one-direction flow of gases within the engine cylinder even though scavenging gases are admitted at both ends of the cylinder. For this purpose the scavenging port area at one end of the cylinder is greater than at the other, and an exhaust port is provided adjacent the end of the cylinder which has the smaller scavenging port area.

Other objects and advantages will be apparent from the specification and claims, and from the accompanying drawings which illustrate what is now considered to be a preferred embodiment of the invention.

Fig. 1 is a sectional view through the engine-and-compressor unit.

Fig. 2 is an enlarged sectional view of the engine cylinder.

Fig. 3 is a fragmentary sectional view of one of the air valves.

The unit shown includes an engine cylinder 10 having reciprocating pistons 12 and 14 to which compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the burning of fuel injected into engine cylinder 10 by one or more devices 32. Air compressed in the air spring cylinders on the power stroke returns the piston assemblies. The assemblies are always maintained at equal distances from the center of the engine by a linkage which may in-

clude the racks 34 on the compressor pistons meshing with a pinion 36.

Intake manifold 38 conducts air to intake valves 40 through which air alternately enters opposite ends of the compressor cylinders. The compressed air leaves the cylinder through discharge valves 42, also at opposite ends of the compressor cylinders, and passes through scavenging manifold 44 through ports 46 and 48 which are uncovered by pistons 12 and 14 at the end of the power stroke, thereby permitting air to be blown through the engine cylinder and exhaust ports 50 and 52 into exhaust manifold 54. Valves 40 and 42 may be the type shown in the Huff Patent No. 1,599,414, dated September 14, 1926, in which, as shown in Fig. 3, each valve includes spring pressed valve blades 49 engaging seats 51.

The engine scavenging ports 46 and 48 are spaced apart in a position to be uncovered by the engine pistons at the outer ends of their stroke. The exhaust ports 50 and 52 are also spaced apart and adjacent the scavenging ports. Each scavenging port 46 or 48 consists of a number of openings in the engine cylinder, as seen more particularly in Fig. 2, and the total area of the openings forming port 46 is considerably larger than the total area of the openings forming port 48. With the scavenging ports communicating with the scavenging manifold 44 and located adjacent the heads of the opposed pistons when they are at the outer ends of their strokes, the cool scavenging air passes over the heads of both pistons as soon as the ports are uncovered.

Each exhaust port 50 or 52 comprises a number of openings and the total area of the openings forming port 52 is considerably greater than the area of the openings forming port 50. Thus the exhaust ports, which are adjacent and between the scavenging ports, are so arranged that the larger exhaust port is at the end of the engine cylinder opposite to the larger scavenging port. Both exhaust ports 50 and 52 are connected to the manifold 54 through which all the compressed gases are discharged to do useful work.

During the strokes of the pistons in both directions, air in the compressor cylinders is delivered under pressure to scavenging manifold 44 to provide for the desired scavenging action when pistons uncover the scavenging ports 46 and 48 during their outward stroke.

When the pistons reach the outer end of their normal strokes (the position shown in Fig. 2), all of the ports are uncovered and cool scavenging air enters at both ends of the cylinder over the heads of the opposed pistons. A relatively large proportion of the scavenging air entering the larger scavenging port 46 establishes substantially a one-direction flow of gases axially of the engine cylinder, the gases discharging primarily through the larger exhaust port 52. Scavenging

air entering port 48 serves to aid in cooling the head of piston 14 before exhausting through port 52.

It is to be understood that the invention is not limited to the specific embodiment herein illustrated and described, but may be used in other ways without departure from its spirit as defined by the following claims.

I claim:

1. In an engine, a cylinder with opposed pistons reciprocating therein, said cylinder having spaced intake ports adapted to be uncovered by the pistons during their reciprocation, and an exhaust port between said intake ports, one intake port being larger than the other. 10
2. In an engine, a cylinder with opposed pistons reciprocating therein, said cylinder having spaced intake ports adapted to be uncovered by the pistons during their reciprocation and an exhaust port adjacent each intake port, said exhaust ports being located between the intake ports, one intake port being larger than the other. 20
3. In an engine, a cylinder with opposed pistons movable therein, said cylinder having axially spaced intake ports and an exhaust port adjacent each intake port, one exhaust port being larger than the other. 25
4. In an engine, a cylinder with opposed pistons movable therein, said cylinder having axially spaced intake ports and an exhaust port adjacent each intake port, one intake port being larger than the other. 30
5. In an engine, a cylinder with opposed pistons movable therein, said cylinder having axially spaced intake ports and an exhaust port adjacent each intake port, one exhaust port being larger than the other, and the intake port adjacent the larger exhaust port being smaller than the other intake port. 35
6. In an engine, a cylinder with opposed pistons reciprocating therein, said cylinder having axially spaced exhaust ports adapted to be uncovered by the pistons during their reciprocation and an intake port adjacent each exhaust port, said exhaust ports being located between the intake ports, one exhaust port being larger than the other. 40
7. In an engine, a cylinder with opposed pistons reciprocating therein, said cylinder having axially spaced exhaust ports adapted to be uncovered by the pistons during their reciprocation and an intake port adjacent each exhaust port, said exhaust ports being located between the intake ports, one intake port being larger than the other. 50
8. In an engine, a cylinder, opposed pistons movable alternately toward and away from each other in said cylinder, said cylinder having scavenging and exhaust ports adjacent one end of the cylinder to be uncovered by one of the pistons in its outward movement, the other end of the cylinder having at least one scavenging port to be uncovered by the other piston during its outward movement, the scavenging port adjacent the exhaust port being smaller than the other scavenging port. 60
9. In an engine, a cylinder, opposed pistons movable alternately toward and away from each other in said cylinder, said cylinder having scavenging and exhaust ports adjacent one end of the cylinder to be uncovered by one of the pistons in its outward movement, the other end of the cylinder having a scavenging port adapted to be uncovered by said other piston during its outward movement, the scavenging port at one end 70

being larger than the scavenging port at the other end.

10. In an engine, a cylinder, opposed pistons movable alternately toward and away from each other in said cylinder, said cylinder having scavenging and exhaust ports adjacent one end of the cylinder to be uncovered by one of the pistons in its outward movement, the other end of the cylinder having a scavenging port adapted to be uncovered by the other piston during its outward movement, the scavenging port at said one end of the cylinder being smaller than the other.

11. In a scavenging system, an engine cylinder, opposed pistons reciprocating in said cylinder, and sets of scavenging ports in said cylinder adjacent opposite ends thereof to be uncovered by the opposed pistons as they reach the outer ends of their strokes, each set including at least one row of ports extending circumferentially of the cylinder.

12. In a scavenging system, an engine cylinder, opposed pistons reciprocating in said cylinder, sets of scavenging ports in said cylinder adjacent opposite ends thereof to be uncovered by the opposed pistons as they reach the outer ends of their strokes, and at least one set of exhaust ports in said cylinder between said scavenging ports and adjacent one set of said scavenging ports.

13. In a scavenging system, an engine cylinder, opposed pistons reciprocating in said cylinder, sets of scavenging ports in said cylinder adjacent opposite ends thereof to be uncovered by the opposed pistons as they reach the outer ends of their strokes, and sets of exhaust ports between said scavenging ports, there being one set of exhaust ports adjacent each end of the cylinder.

14. In a scavenging system, an engine cylinder, opposed pistons reciprocating in said cylinder, scavenging ports adjacent opposite ends of said cylinder to be uncovered by the opposed pistons as they reach the outer ends of their strokes, and at least one exhaust port between the scavenging ports and adjacent the scavenging port at one end of the cylinder, the scavenging port to which the exhaust port is adjacent being smaller in area than the scavenging port adjacent the opposite end of the cylinder.

15. In a free-piston engine and compressor, an engine cylinder, opposed pistons reciprocating therein, at least one compressor cylinder, a compressor piston in said compressor cylinder and movable with one of the pistons in the engine cylinder, scavenging ports adjacent opposite ends of the engine cylinder to be uncovered by the pistons as they reach the outer ends of their strokes, and a manifold connecting the compressor cylinder to said scavenging ports for delivery of compressed gases to said engine cylinder adjacent opposite ends thereof and in front of both pistons.

16. In a free-piston engine and compressor, an engine cylinder, opposed pistons reciprocating therein, at least one compressor cylinder, a compressor piston in said compressor cylinder and movable with one of the pistons in the engine cylinder, scavenging ports adjacent opposite ends of the engine cylinder to be uncovered by the pistons as they reach the outer ends of their strokes, a manifold connecting the compressor cylinder to said scavenging ports for delivering compressed gases to said engine cylinder adjacent opposite ends thereof and in front of the pistons therein, and exhaust ports in said engine cylinder.
